US00D585047S

(12) **United States Design Patent**
Chen

(10) **Patent No.:** **US D585,047 S**
(45) **Date of Patent:** **** Jan. 20, 2009**

(54) **MOBILE PHONE**

(75) Inventor: **Yi-Cheng Chen**, Sinjhuan (TW)

(73) Assignee: **Hannspree, Inc.** (TW)

(**) Term: **14 Years**

(21) Appl. No.: **29/306,801**

(22) Filed: **Apr. 16, 2008**

(51) **LOC (9) Cl.** **14-03**

(52) **U.S. Cl.** **D14/143; D14/138 AA**

(58) **Field of Classification Search** **D14/137, D14/138 R, 138 AA, 138 AD, 138 C, 138 G, D14/143-144, 147-148, 156, 218, 247-248, D14/341-347, 390, 399, 455-456, 496; D13/164, D13/168; D16/208; D21/329, 331, 333, D21/517; 343/702; 348/14.01-14.02; 361/814; 379/433.01-433.13; 439/165; 455/90.3, 455/556.1-556.2, 566, 575.1, 575.3, 575.4**
